[57] CLAIM

The ornamental design for a sponge brush with coupling for attachment to an extension handle, as shown and described.

DESCRIPTION

FIG. 1 is a front elevational view of the sponge brush with coupling for attachment to an extension handle showing my new design;

FIG. 2 is a rear elevational view thereof;

FIG. 3 is a left side elevational view thereof;

FIG. 4 is a right side elevational view thereof;

FIG. 5 is an enlarged top plan view thereof; and,

FIG. 6 is a bottom plan view thereof.

FIG. 1

FIG. 2

FIG. 3

FIG. 4

FIG. 5

FIG. 6
